William L. Butcher

UNITED STATES PATENT OFFICE.

WILLIAM L. BUTCHER, OF FLORA, INDIANA.

FENCE-GATE.

1,346,395.

Specification of Letters Patent.

Patented July 13, 1920.

Application filed December 2, 1919. Serial No. 341,871.

To all whom it may concern:

Be it known that I, WILLIAM L. BUTCHER, a citizen of the United States of America, residing at Flora, in the county of Carroll 5 and State of Indiana, have invented certain new and useful Improvements in Fence-Gates, of which the following is a specification.

The primary object of the present invention has particular reference to a fence gate formed of a metallic skeleton framework with horizontally disposed slats or rails detachably connected to the skeleton framework so that any one, or all of the 15 slats may be removed from the frame for purposes of repairing a damaged slat or for the insertion of a new one.

A further object of the invention consists in providing a fence gate embodying normally spaced bars, between which the fence rails or slats are adapted to be inserted with clamping devices arranged at opposite sides of the rails and being supported thereon for holding the same in fixed position relative 25 to the gate frame.

With the above and other objects in view, the invention consists in the novel form, combination and arrangement of parts herein fully described and shown in the accompanying drawings, wherein like reference characters indicate similar parts throughout the several views.

In the drawings,

Figure 1 is a front elevational view of 35 a fence gate constructed in accordance with the present invention,

Fig. 2 is a top plan view thereof,

Fig. 3 is a detail sectional view taken on line III—III of Fig. 1 showing the clamping strips for retaining the horizontal rails 40 in position,

Fig. 4 is a cross sectional view taken on line IV—IV of Fig. 1,

Fig. 5 is a cross sectional view taken on line V—V of Fig. 1 showing the spaced gate bars with roller bearings upon the rivet connections thereof with the rail slats positioned between the rollers,

Fig. 6 is a sectional view similar to Fig. 5 50 of a modified form of the invention illustrating the employment of rivets or bolts without the use of rollers and

Fig. 7 is a cross sectional view taken on line VII—VII of Fig. 1 showing the sliding 55 gate latch.

While the present drawing discloses a gate

construction, it is to be understood that this invention is also adaptable in the manufacture of fences, and it is therefore not intended to limit the invention to a gate. The 60 form of gate herein disclosed embodies a skeleton metallic framework formed of spaced pairs of rail supporting bars, each pair including an angle bar and a straight strip with connecting bolts between the bar 65 of each pair with rollers upon said bolts between said bars and between which rollers the rail slats are adapted to move. Crossed braces formed of angle irons extend between the pairs of end bars, while hinge members 70 arranged in vertical alinement extend between one pair of end bars and are connected to the adjacent end of the crossed braces. Adjacent each pair of end bars, a pair of clamping bars is provided and are 75 adapted for engagement with the crossed braces and removable rail slats for holding the slats in fixed position relative to the metallic framework of the gate, while a sliding latch extends between one pair of 80 clamping bars and the adjacent pair of end gate bars opposite to the said hinges. A modified form of the invention has the elimination of the rail slat engaging rollers and provides for the bolts connecting the 85 pairs of fence bars for supporting the rail slats.

Referring more in detail to the accompanying drawing, there is illustrated a gate embodying spaced pairs of end bars, each 90 pair including an angle iron 8 and a straight bar or strip 9 connected together by the rivets or bolts 10 shown in Fig. 5 with rollers 11 upon said bolts intermediate the bars 8 and 9 for spacing the bars and also to support the rail slats 12 as illustrated. The end bars 8 and 9 of the gate are maintained in spaced relation by the crossed brace rods 13 connected together at their crossing points as at 14 while the opposite ends thereof are connected to the upper and lower ends of the bars 8 and 9 as shown in Fig. 1. At points spaced inwardly of the opposite pairs of end bars 8 and 9, are similarly formed pairs of bars, designated by like reference 100 characters 8 and 9 with rollers 11 mounted upon the bolts 10 with the rail slats 12 sliding therebetween. The inwardly positioned pairs of bars 8 and 9 are held immovable relative to the skeleton gate frame by bolt 105 connections 15 passing through the crossed braces 13 and the inner bars 8 and 9.

- Hinge devices are associated with one pair of end bars as illustrated in Figs. 1 and 2 and comprise in detail a metallic strap bent into loop formation as at 16 for mounting upon a bearing with the ends of the strap lying juxtaposed as illustrated in Fig. 3 with the ends extending between the adjacent bars 8 and 9, and secured thereto by the fastening device 16', one end of the strap hinge being angularly bent as at 17 for engagement with the angle bar 8 while the other end of the strap hinge is relatively extended as at 18 for attachment to the adjacent crossed braces 13 by fastening devices 19, more clearly shown in Figs. 1 and 2. As illustrated in Figs. 1 and 5, the rail slats 12 are slidably disposed between adjacent rollers 11 with the slats arranged in close relationship at the lower end of the gate and spaced wider apart at the upper end thereof. This arrangement of the slats is found to be advantageous in preventing a passage through the rail slats of smaller animals.
- Clamping bars are associated with the rail slats and crossed braces and are of like construction, a clamping bar being positioned at each end of the gate and including a pair of post bars 20 and 21 arranged at opposite sides of the rail slats 12 with the bar 21 secured to the crossed brace 13 by a rivet or like fastening device 22. A headed bolt 23 is carried by said bar 21 and projects through an opening formed in the bar 20 with a thumb nut 24 received upon the threaded end thereof, while rollers 25 are mounted upon the bolts 23 between the bars 20 and 21 for resting upon the rail slats 12. A sliding latch 26 is loosely mounted between one pair of clamping bars 20 and 21 and adjacent end bars 8 and 9 with a transversely extending pin 27 playing between the clamping bars and end bars for limiting the sliding movement of said latch.
- From the above detailed description of the invention, it is believed that the construction and method of assembling the different parts of the gate will at once be apparent, it being noted that the gate frame bars 8 and 9, and the crossed braces 13 are permanently connected and are at all times relatively immovable. The hinge straps 16 are permanently connected to one set of end bars 8 and 9 and the adjacent portions of the crossed braces. After positioning the rail slats 17 between aligned pairs of bolt supporting rollers 11, and the clamping bars 21 and 22, the thumb nuts 24 carried by the clamping bars are tightened to clamp said bars upon opposite sides of the rail slats 12, and clamping bars 21 are fixed to the crossed braces 13, said rail slats are held immovable

relative to the frame structure of the gate. Should one of the rail slats become damaged the same may be readily removed by loosening the thumb nuts 24 and shifting the damaged rail slat longitudinally of the gate, for purposes of repair or for the insertion of a new slat.

A modified form of the invention is shown in Fig. 6 and embodies bar sections 8' and 9' similar to the bars 8 and 9 in the preferred construction, but in this form of the invention, the connecting bolts 10' between the bars directly engage the rail slats 12' and are free of carrying rollers.

As above stated, it is intended that this invention should not be limited alone to the manufacture of gates but is to include a fence construction wherein the different rail slats of the fence may be similarly mounted and removed if desired, and while there are herein shown and described, the preferred embodiments of the invention, it is nevertheless to be understood that minor changes may be made therein without departing from the spirit and scope of the invention, as claimed.

What is claimed as new is:—

1. A device of the class described comprising spaced pairs of connected bars, rail slats freely slidable between the bars of each pair and means independent of said bars and anchored relative thereto for holding said bars and the rail slats relatively immovable.

2. A device of the class described comprising spaced pairs of connected bars, rail slats between the bars of each pair, and means for holding said bars and rail slats relatively immovable, said means comprising clamping bars anchored relative to said spaced bars and inclosing the spaced bars and slats.

3. A gate construction embodying spaced pairs of connected bars, rail slats freely slidably positioned between said bars, crossed braces extending between the extreme pairs of connected bars, clamping bars anchored to said cross braces and engaging said slats for holding the same immovable relative to said bars and hinges carried by one pair of bars at one end of the gate.

4. A gate construction embodying pairs of spaced connected bars, crossed braces connecting the end pair of bars, rollers journaled between each pair of bars, rail slats slidable between said bars and guided by said rollers and clamping bars inclosing the slats and secured to said crossed braces for holding the rail slats immovable relative to said supporting bars.

In testimony whereof I affix my signature.

WILLIAM L. BUTCHER.
